DEVICE FOR FLUSHING WATER-CLOSET PANS

Application filed March 28, 1929. Serial No. 350,688.

The present invention has reference to improvements in devices for flushing water-closet pans. Heretofore water-closet pans were flushed by pulling a chain, or moving 5 a lever or other hand operated means, while according to the present invention the flushing mechanism is operated by the foot.

The advantages of this invention consist, firstly, in added cleanliness, as the invention 10 avoids contact of the hand with the flushing device, and secondly, in easy and reliable operation, and also in duration, and in improved appearance. The improved apparatus may be used on any kind of water-closet, 15 whether flushed by lever, chain or button.

The device in accordance with the present invention consists essentially in a push button fitted in a casing which is embedded in the floor, which push button moves vertically 20 when pressed downwards with the foot. When this button is thus pressed downwards, it causes a lever to oscillate. To this lever is attached a cable which passes through pulleys and transmits movement to the actuating element 25 of the water discharge apparatus. In case it becomes necessary to lengthen the range of movement given by the foot to the push button, suitable pulleys and multiplying gear are mounted upon the cable.

30 In order that the invention may be readily understood the same is described in connection with the accompanying drawings.

Fig. 1, is a schematic elevation of the device as applied to a flushing apparatus having 35 an elevated water supply tank, ordinarily operated by hand.

Fig. 2, is a vertical longitudinal section of the push button mechanism, and

Fig. 3, is a cross vertical section, of the 40 same, Fig. 4, is a vertical longitudinal section of the multiplying gear, and

Fig. 5, is a front view of the multiplying gear.

Like references indicate similar parts 45 throughout the drawings.

The example illustrated in Fig. 1, comprises the push button A, and the multiplying gear B; the latter is necessary in the present case, because the flushing device of 50 the raised water tank type, such as C, is pro-

vided with an operating lever D, having a movement of a longer range than that of push button A. Fig. 1, illustrates the means of adjusting the different elements, namely, the push button A, is embedded in the floor, 55 the button proper only protruding. The cable operated by said push button passes through a pipe 1, embedded in the floor and which leads to the casing of the multiplying gear B. The latter is placed in an angle 60 formed by the floor and the wall, and from there starts another pipe 2, which is embedded in the wall and which rises to a level slightly lower than that of lever D. Cable 3, which passes through pipe 2, passes around 65 a pulley 4, and then through a horizontal pipe 5, fixed to the wall; and lastly it passes through another pulley 6, fixed to the end of this pipe. Cable 3, is then attached to a stretcher 7, hooked to lever D, of the discharge apparatus. The object of this stretcher is to allow adjustment of the cable tension. 70

Should the multiplying gear not be necessary, the cable leading from push button A, 75 passes directly through guide pulleys to the water discharge apparatus. This requires no illustration.

Figs. 2 and 3, illustrate the push button in detail. It comprises a rectangular casing 8 open above, provided all around with a horizontal flange 9, having a small vertical rib 10. This casing is embedded in the floor in such manner that rib 10 is flush therewith. In this casing is placed another casing 11, 80 also open above, and having flanges 12, which fit exactly upon flanges 9 of the outer casing. A cover 13, having a central orifice for the push button proper 14, covers casing 11, and fits within rib 10, and is fixed, together with 85 casing 11, upon casing 8, by means of screws 15. The lateral walls of casing 11, are provided with an orifice through which passes a horizontal transversal pin 16, which can rotate freely and is kept in a longitudinal 90 position by the walls of casing 8. Upon the center of this pin is mounted a lever 17, which can also rotate freely upon said pin but which is prevented from moving laterally by means 95 of a screw 18, the end of which enters a circu- 100

lar groove in the pin. One of the ends of said lever is in the shape of a cam and receives the pressure of rod 19, formed by a central lower projection of button 14. The other end of lever 17, is provided with a cut 5 in which is tied the end of cable 20, which operates the water discharge apparatus, either directly or indirectly. Button 14, forms a hollow cylinder closed above by a spherical top piece so as not to offer any 10 sharp projections above the floor. The cylindrical part acts as a guide to the button in its vertical movement and runs tightly in a cylinder flange 21, of cover 13. This cylindrical part of the button is cut at its lower 15 end over a part of its circumference to allow passage of pin 16, and its lower edge is provided with a flange 22, which limits the upward movement of the push button when the latter abuts against the lower edge of the 20 cylindrical part of the cover.

Normally the push button protrudes above the floor a few millimeters, being held in this position by the tension transmitted to the cable by the flushing device. When pushing 25 down said button with the foot, the button causes lever 17 to oscillate, lever 17 pulling on cable 20, which starts the water discharge apparatus.

30 Casings 8 and 11, are provided at one end with an orifice through which passes cable 20. The multiplying gear illustrated in Figs. 4 and 5, comprises also a casing 23 which is embedded in the angle formed by the floor and the wall. This casing is open at the front and at its upper back part; in front it is provided at each side with a rib 24. This casing contains another casing 25, which is open in front, above and below, and which comprises lateral ribs 26, for adjustment with the ribs 35 of the other casing. The outer casing is higher than the inner one sufficiently to allow the latter to be passed through the opening of the outer casing existing between the level of the floor and the upper part. Said inner casing is therefore placed in position by introducing it first horizontally and then vertically until it rests at the bottom of the outer casing; when the inner casing is in position, the ribs 40 are screwed together and the opening in the outer casing is closed by a screwed cover 27. The inner casing carries two horizontal cross pins 28, in the same manner as pin 16 in casing 11. Upon the lower pin rotates freely a 45 pulley 29, upon which coils cable 20, and which is integral with a toothed wheel of large diameter 30. The latter engages a small pinion 31, integral with a large pulley 32, which rotates freely upon the upper pin. 50 On this pulley 32 is coiled cable 3, which leads to the flushing device proper. As will be readily understood, a short movement of cable 20, produces a long movement of cable 3, which is the object of the multiplying gear.

60 65 Claims:

1. An improved device for flushing water-closet pans of the type operated by a pull chain or cable, consisting essentially of a foot operated push button, mounted in a casing embedded in the floor, and slightly protruding above the floor, which push button operates a lever which is also mounted in said casing beneath the push button and protected thereby, said lever having an arm operating within the casing so as to pull the cable which operates, directly or indirectly, the water discharge apparatus. 70

2. An improved device for flushing water-closet pans, in accordance with claim 1, in which the cable or cables pass around pipes embedded in the floor and in the wall, and through guide pulleys, to the water discharge apparatus, thereby being protected from injury and corrosion. 80

3. An improved device for flushing water-closet pans comprising a foot operated push button, mounted in a casing embedded in the floor, and slightly protruding above the floor, which push button operates a lever which is also mounted in said casing so as to pull the cable which operates, directly or indirectly, the water discharge apparatus, a multiplying gear placed between the push button and the water discharge apparatus, consisting of a set of gears operated by means of a pulley 95 on which coils the cable coming from the push button, and which actuates another pulley on which is coiled the cable leading to the water discharge apparatus. 90

4. An improved device for flushing water-closet pans, comprising an outer casing which is embedded in the floor, an inner casing containing the operating mechanism which is placed inside the outer casing, a cover for the inner casing screwed to the outer casing and thereby securing the inner casing in place, a pin, a lever mounted upon said pin and which is connected with the cable leading to the water discharge apparatus, and a push button guided in said cover by a cylindrical part which rests by means of a central projection upon said lever, said push button having a flange engaging under said cover to prevent removal. 100

5. An improved flushing device for flushing water-closet pans, comprising a foot operated push button, mounted in a casing embedded in the floor, and slightly protruding above the floor, which push button operates a lever which is also mounted in said casing so as to pull the cable which operates, directly or indirectly, the water discharge apparatus, a casing to be embedded, a casing containing multiplying gear and which is screwed to the embedded casing, a front cover for the embedded casing, two pins, a small pulley for the cable leading from the push button integral with a large toothed wheel and rotating upon one of the pins, and a large pulley for the cable leading to the water discharge apparatus, integral 115 120 125 130

with a pinion and rotating upon the other pin
so as to cause the pinion to mesh with the
toothed wheel.

5 In testimony whereof we affix our signa-
tures.
